UNITED STATES PATENT OFFICE.

CHARLES L. NORTON, OF HUDSON, NEW HAMPSHIRE, ASSIGNOR TO ASBESTOS SHINGLE COMPANY, OF NASHUA, NEW HAMPSHIRE, A CORPORATION OF NEW YORK.

MACHINE FOR MAKING CONCRETE SLABS OR PLATES.

1,140,702.

Specification of Letters Patent. Patented May 25, 1915.

Application filed July 15, 1914. Serial No. 851,223.

To all whom it may concern:

Be it known that I, CHARLES L. NORTON, a citizen of the United States, and resident of Hudson, in the county of Hillsboro 5 and State of New Hampshire, have invented new and useful Improvements in Machines for Making Concrete Slabs or Plates, of which the following is a specification.

My invention relates to the art of continuous production of concrete slabs or plates, such as typified by the machine shown and described in United States Patent No. 979,548, dated December 27, 1910, and has for its object the improvement of the operation 10 and the product of such machines, in respect particularly to uniformity and regularity.

Especially, the object is to produce finished concrete plates or slabs of uniform 15 thickness, density and strength.

Since the instruments by which the materials composing the concrete are compressed are, of practical necessity, unvarying in their action after having been once adjusted 20 for a given course of operation, these improvements are addressed to the regulation of the supply of material which is afterward conveyed to the compressing factors.

An example of the materials to be treated 25 is described in the above mentioned United States patent. As it is fed to the slab or plate making machine in a dry, comminuted state, it is capable of flowing in some measure like a liquid, provided proper conditions 30 are preserved. And, like a liquid, this material, if made to assume columnar proportions, exerts static pressure in all directions, somewhat like a column of liquid, although, unlike a liquid, it is compacted or compressed 35 in proportion to the amount of pressure sustained. The invention herein described thus presents two aspects, one that of a method or process, characterized by the continuous feeding of comminuted dry 40 material to a conveyer under a substantially constant static, self produced pressure, or, under the static pressure, self produced in the material by the maintenance of a substantially constant columnar head over the 45 point of delivery to the conveyer, the other that of a machine by which the above characterized process or method may be carried on. Claims for the method are presented in an application for United States Letters 50

Patent filed concurrently herewith, Serial 55 No. 851,224, the claims herein being addressed to the machine.

In the drawings hereto annexed, which illustrate the invention, Figure 1 is a diagrammatic representation, in longitudinal 60 elevation, of a concrete slab or plate making machine which embodies the invention; Fig. 2 is a plan view of the hopper-end of the machine; Fig. 3 is a longitudinal central vertical section of the hopper-end of the 65 machine; and Fig. 4 is a vertical cross section of the machine at the line 4—4 of Fig. 3.

Referring to Fig. 1 (and also to said United States Patent No. 979,548 for a description of a machine of the type under 70 consideration) the numeral 1 represents a belt conveyer which may be a single endless belt, (or a pair of conveyers placed end to end, as shown in the said patent) driven at constant speed in the direction of the arrows 75 drawn adjacent to said conveyer. This conveyer 1 will be referred to as the main conveyer, since another conveyer enters into the organization of the machine. 2, 2, and 3, 3, are the press rolls, which rotate in the 80 direction indicated by arrows; 4 is a rotating cutter which grooves the material M, dividing it into separate plates or slabs; 5 is a water supply device which wets the material 85 after it has received a preliminary dry-pressing by the press rolls 2, 2; 6 is the delivery roll, 7 a leveling worm which reduces the depth of the material which proceeds from the hopper A; 8 is a rotating brush, which completes the work of reducing the 90 thickness of material to a uniform dimension; 9 is a side-trimmer, which trims the edge of the layer of material so as to deliver a layer of uniform width to the press rolls, and 10 is a table or support over which the 95 belt-conveyer, or main conveyer, 1, passes. There is, of course, a side-trimmer 9 on each side of the main conveyer. On the under-side of the main conveyer 1 there is a rotary wiper or brush L, which serves to clean 100 the surface of the conveyer and to remove from it part of the moisture remaining after the plates S have been removed from the end of the conveyer when it passes over the delivery roll 6.

It will be observed that the machine above briefly described differs from that which is the subject of United States Patent No.

979,548, in that the main conveyer is here shown as a single endless belt, whereas in the said patent the machine is specifically characterized by two belt conveyers, placed end to end, with a gap between, which is spanned by a bridge, over which the first belt pushes the layer of dry-pressed material to the second belt, which is wet. While the machine of that patent has been successfully employed in the commercial manufacture of concrete plates, its efficient behavior was conditioned on sundry nice adjustments of machine and materials, particularly in relation to the transit of material over the stationary bridge between the belts. The machine herein depicted and described comprises sundry inventions and improvements not essentially related to the subject matter herein claimed, and these improvements, which make possible the employment of a single endless main conveyer, and obviate the necessity of the stationary bridge aforesaid, with its concomitant difficulties, are the subject of another application, filed currently herewith, Serial No. 851,858.

Passing now to the subject matter with which the present specification is more intimately concerned,—there is mounted over the receiving end of the main conveyer a hopper A, having an open bottom close to the surface of the main conveyer, and a lateral gateway A', opening in the direction of the travel of the conveyer surface. In its preferred form, the hopper A is a cylindrical stand-pipe, which has, therefore, circular cross section, well adapted to the uniform distribution of static pressure through the mobile material contained in it. Though it is to contain solids only, this hopper A is essentially a pressure tank. The top of the hopper A is also open, and supply pipes E and G deliver comminuted material into the top of the hopper. Within the hopper A, there is a shaft J (Fig. 3), rotatably mounted, and armed with crossed, flat paddle blades K, K, which continually stir the material and prevent it from caking or arching, in other words, by agitating the material the paddles K maintain it in a quasi fluid condition, conducive to the production of fluid pressure throughout its mass, a pressure which is maintained specifically uniform all over the bottom of the hopper A, by the following means.

Since the comminuted solid material is made to behave practically as if it were a fluid, the static pressure in the column within the hopper A increases in direct proportion to the depth of the column. In order to maintain the desired uniform static pressure at the bottom of the hopper A, where the material is delivered to the main conveyer 1, the column of material is kept at constant height. The preferred specific mode of maintaining uniform and constant

pressure at the bottom of the hopper is to produce a continual overflow from the open top of the hopper. To this end, the following arrangement of apparatus is found suitable. An endless belt B, termed the return conveyer, is mounted on rolls b and b', below the main conveyer, so as to catch the surplus material, purposely supplied and purposely removed by the worm 7, brush 8, and trimmers 9. The surplus material pushed off the main conveyer 1 is guided to the return conveyer B by the inclined plates 11, 11, (Figs. 3 and 4). The return conveyer carries this surplus to the chute C, which in turn delivers the material to the bucket hoist D. The bucket hoist D dumps the material through funnel I into chute G, whence it falls into the top of the hopper A. Meanwhile a fresh supply of material is introduced by means of appropriate apparatus, such as the chain or bucket hoist H and pipe E. The return supply and fresh supply together continuously introduce into the top of the hopper A more material than emerges from the bottom of the hopper, so that there is a continual spill from the top of the hopper, into the lip-chute F, which delivers the spill to the return conveyer B. The agitating paddles K preserve the column of material in the hopper A in a mobile condition, so that as it descends, the material becomes progressively more and more compacted, sustaining therefore an initial consolidating pressure, constant in degree and uniform in distribution, at the point of delivery to the main conveyer 1. Furthermore, in order to have the band or layer of material which is to be subjected to the succeeding stages of compression, uniform in transverse section as well as uniform in density, the lateral gateway A' is so proportioned that it delivers a band of material substantially thicker and wider than the desired final proportions. Part of this designedly supplied surplus is scraped off by the right and left pitched worm 7, which pushes the material sidewise off the edges of the main conveyer 1. Then the brush 8, which is a cylinder armed with short wooden or metal splints, levels off the top surface of material still more, giving it a "finishing cut." The predetermined thickness of material being thus obtained, the side scrapers 9 trim the band of material at its edges, throwing this surplus off, to be caught by the return conveyer B. Then the material is compressed further by the dry press rolls 2, 2, is then wetted with water falling from the dampener 5, transversely grooved by the rotating knife-frame 4, wet pressed by the press rolls 3, 3, and finally removed, in individual slabs, each of which is slid on to a steel plate as it comes off the main conveyer 1.

The details of mechanism are illustrated 130

in Figs. 2, 3 and 4, and require no further extended explanation, in view of the foregoing.

What I claim, and desire to secure by 5 Letters Patent, is:

1. In a machine of the character described, the combination of a conveyer, a tubular hopper with a delivery orifice at one side at its lower end and a spill opening at a point above its lower end, the conveyer constituting the bottom closure of the hopper, and means to feed dry material to the hopper, in excess of the material-removing capacity at said lateral orifice at the lower end of the hopper.
- 10 2. In a machine of the character de-

scribed, the combination of a conveyer, a tubular hopper with a delivery orifice at one side at its lower end and a spill opening at a point above its lower end, the conveyer constituting the bottom closure of the hopper, means to feed dry material to the hopper, in excess of the material-removing capacity at said lateral orifice at the lower end of the hopper, and means to 20 agitate the material in the hopper.

Signed by me at Boston, Massachusetts, this thirteenth day of July 1914.

CHARLES L. NORTON.
